UNITED STATES PATENT OFFICE.

EDWARD J. COLBY, OF CHICAGO, ILLINOIS.

WATCHMAN'S TIME-RECORDER.

SPECIFICATION forming part of Letters Patent No. 359,999, dated March 29, 1887.

Application filed January 13, 1886. Renewed February 7, 1887. Serial No. 226,807. (No model.)

To all whom it may concern:

Be it known that I, EDWARD J. COLBY, a citizen of the United States, residing at Chicago, in the county of Cook and State of Illinois, have invented certain new and useful Improvements in Watchmen's Electric Clocks, of which the following is a specification.

My invention relates to clocks such as are used to indicate the course of a watchman over his stations by means of a needle which, when the circuit is closed by the watchman, punctures the rotating dial. Its objects are to provide means whereby the clock can be used for a varying number of stations, and whereby the watchman, in order to make the needle operate, must be at his station at a given time, and whereby he may move in either direction over his course. These objects I attain in the manner indicated by the mechanism illustrated 20 in the accompanying drawings, wherein—

Figure 1 is a plan view of the clock open, with parts shown in dotted lines. Fig. 2 is a similar view with the clock mechanism removed, showing the electro-magnets and the wires in the case. Fig. 3 is a view of the back of the clock with rear lid open and commutator exhibited. Fig. 4 is a diagram of stations and the commutator in the center, showing the course of the wires when the machine 25 is arranged for thirty-six stations. Figs. 5, 6, and 7 are detail views of the commutator. Fig. 8 is a section of the electro-magnet and pivoted armature and needle.

Like parts are indicated by the same letter 35 in all the figures.

A is the case; B, the lid, having a brass mat, C, and a glass front, D; E, a stationary metal disk in front of the clock mechanism; F, a central rotating metal disk; G, a clamp over 40 the disk F; H H, electro-magnets, either simple or compound, as the case may be. I is the case-lock.

J J are the hinged sides of the case, arranged so as to be turned down when it is desired to have access to the interior of the clock.

K and L are apertures, through which to have access to the interior of the clock for the purpose of regulating or stopping or starting it.

M is a paper dial which rests on the disk E, and is clamped to and rotates with the disk F.

This dial is held down, so as to receive the points of the needles, by means of the mat C. It is divided into concentric rings, as shown, there being any desired number of them, and 55 these are divided into time-spaces by radial lines. Each ring has twelve hour-spaces, and each is numbered, so that when six needles are used each, if operated at the same time, will puncture its particular ring at the same time-mark, the needles being distributed at suitable distances about the dial. This is done by placing the electro-magnets each with its needle secured to its armature about the dial, each magnet being set so as to bring its needle to 60 the proper point, as shown in Fig. 2. Here the electro-magnets are arranged about the commutator, and in Fig. 1 they are arranged in the same manner, and parts of them can be seen, while their needle-points are seen protruding through the dial, each in its own ring and all in the same hour-mark. I use six needles and arrange them at equal distances about the dial. The needles are shown protruding through the paper dial at 65, as if all had been 70 operated at the same time.

P P are pins through the bottom of the case, which serve to form part of the circuits.

R is the rear lid of the case, and it carries the circuit-closers P' P', which connect with 80 the wires from outside the case, and when the rear lid is closed bear upon the pins P P, and thus close the connection with the wires within the case.

S is the commutator, one side of which is 85 seen in Fig. 2 and the other in Fig. 3.

T are the wires which pass—one from each station—to a magnet, through the parts P' and P, and thence to one plate of the commutator. In the figures only six of these wires are shown; 90 but in the diagram six sets of six wires each are provided for, and one set of six wires is shown. This would necessitate more of the parts P and P', and the magnets would then be compound, as indicated in the diagram. 95 Each set of six stations has a series of wires—one from each station—through its magnet to one plate, although I have shown but one wire from each set after the first.

U is a wire from the battery to the clock. 100 It is shown loose in Fig. 2, because the clock mechanism to which it is attached is removed.

V is a wire from the battery to the stations. It is shown in the diagram as leading to a wire which forms a circuit about the stations in set one, though of course it must connect with each 5 station. At each station is a suitable device for closing the connection between the wire V and the wire T.

The commutator consists of a plate of insulating material, S', having the groove S² and 10 apertures S¹⁰ S¹⁰, through which the wires from within the case pass to the plates Y and Z, which are arranged in concentric circles on the opposite side of the plate S'. The clock-stem passes through this plate and carries the trailing hand Z', which sweeps over the inner circle of plates. It also carries the sleeve S⁸, 15 which is rotated in the opposite direction by the mechanism S⁴ S⁵ S⁶ S⁷, and carries the trailing arm or hand Y', which sweeps over the outer 20 circle of plates. The operation of these parts is as follows: The clock-stem S³ rotates in one direction, carrying the trail Z' and rotating the pinion S⁴. This pinion meshes with the gear S⁵, which is supported on the same shaft 25 with the wheel S⁶. This wheel meshes with the idle-pinion S⁷, which in turn rotates the sleeve S⁸ by engaging its lower cogged end. This of course rotates the sleeve in the opposite direction from the stem, and consequently 30 the trails are carried in opposite directions.

S⁹ is a cap, which, when the commutator is out of use, can be substituted for the trailing hands, and thus puts all the plates permanently into connection. The plates lying 35 between the same radial lines are connected, as shown. The needle from the armature may pass up between the cores of the magnet, or at one side, as shown.

O is the needle; O' O', the coils of the electro-magnet; O², the pivoted armature to which the needle is secured; O³ O³, the cores of the same. In Fig. 8 the needle is shown passing up through the connecting-piece of the cores and between the coils.

45 The trail or trailing hand, which moves over the metal plate in the commutator, is secured to the stem of the clock just as the minute-hand, or hand which makes the circuit in one hour, is secured in clocks as usually mounted.

50 The commutator is, in fact, substituted for the dial and the trail for the minute-hand. The reverse trail is mounted and operated as shown.

The clock mechanism is of any style. The dial, as shown in Fig. 1, is made by striking on the 55 surface thereof a series of concentric circles, and then dividing these into time-spaces by a series of radial lines. Each space then becomes a time-space, and may be marked accordingly. Each circle has its own magnet

60 and needle, as described; and in order to avoid the necessity of placing all the needles in the same radial line, and yet construct the dial so that all of the needles can commence to operate at the same hour, I place the needles in any 65 convenient position, and then put the same hour-mark in the time-space directly above them all. By then carrying out the hour-marks

in each circle the desired result is attained, as shown.

The operation of my invention is as follows: 70 The device is arranged for six watchmen and each has six stations. One wire from each station in each of the circuits of six stations runs through one and the same electro-magnet and thence to one plate of the commutator. From 75 this it will be readily seen that the watchman working these stations must at a given time be at that particular station whose wire connects with the plate over which the trail of the commutator is passing. The commutator 80 passes around in one hour, its hand being on each plate ten minutes. When the circuit is closed by the watchman, the needle of the compound electro-magnet through which the wire passes punctures the rotating dial and shows 85 what needle is used and what hour the circuit was closed. Each station has its particular time, and hence the station is indicated by the time of the puncture. The same remarks apply to each set of six stations and each magnet. 90 Now, if a less number of stations are to be used, the number of plates on the commutator could be varied. If the number of stations in each set of stations be different, the operation is the same, but the distance of time 95 between the stations in each set would be different. If only one alarm is to be given from each set of stations, as in case it is desired to use but one watchman for a time and have him go over the whole route, sounding but one 100 alarm for each set of stations, the ring can be substituted for the hands and trails of the commutator, and the plates be thus brought permanently into the circuit. The dial will then show the time at which each needle is used. 105

The inner circle of commutator-plates and the inner hand and trail are designed to permit the watchman to traverse his set of stations in one direction, and then, after waiting half an hour, until the other trail reaches the station 110 at which he has stopped, to pass over his stations in the reverse order. It also permits him to follow one hand or trail until he reaches the other hand, when he can turn about and follow that. This permits him to keep an irregular beat, and at the same time gives the proprietor the benefit of the commutator to keep a record of the movements of the watchman. 115

The electro-magnets are such as are commonly employed for similar purposes, the needle being secured to the armature and sticking up between the cores. 120

I claim and desire to secure by Letters Patent—

1. In an electric clock for watchmen, the combination of an insulating-plate, a series of rings of independent metal plates secured thereon, a clock, and a trail which is moved over the plates by the mechanism of the clock. 125

2. The combination of a clock connected with the battery, a commutator consisting of a disk of insulating material and a series of plates arranged in a circle thereon, each con-

nnected with the circuit, and a trail which is connected with and rotated by the clock and passes over the plates.

3. A commutator consisting of a double series of plates arranged in concentric circles and secured to a disk of insulating material, and two trails which pass, respectively, over the circles of plates and are rotated in opposite directions from the same center.

10 4. In a watchman's electric clock, the combination of a series of electro-magnets, a rotating dial, and a commutator, as shown.

5. In a watchman's electric clock, the combination of a case, a clock mechanism con-

nected with the battery, a series of electric 15 magnets through which the wires from the stations pass, and a commutator, as described, the wires from the magnets passing one to each plate of the commutator, whereby the circuit is alternately opened and closed at regular intervals, as described.

Signed at Chicago, Illinois, this 2d day of January, A. D. 1885.

EDWARD J. COLBY.
